FLUORESCENT BALLAST

Edwin E. Turner, Jr., West Roxbury, Mass., assignor to Tobe Deutschmann, Canton, Mass.

Application November 28, 1945, Serial No. 631,424

3 Claims. (Cl. 315—243)

1

The present invention relates to ballast units for fluorescent lamp lighting and has for its purpose the construction of a simple ballast unit avoiding transformers and large chokes.

In the art of fluorescent lighting, it is well known that considerably higher voltage is required to start the fluorescent discharge in the tube than to continue it after ionization in the tube has occurred. In order to provide the higher starting voltage, it is customary to use a transformer, usually of the auto-transformer type, and in addition to this a choke or two in series with each fluorescent tube in the system. When the discharge has started and the higher voltage is no longer necessary, the auto-transformer is undesirable, but since it is in the starting circuit, it remains in the circuit during the running operation.

In the present invention a fluorescent ballast unit has been invented, which will provide the necessary higher voltage under starting conditions while under running conditions it will have substantially no effect in the operating circuit so that efficient running operation will be obtained with unity power factor. A desired phase shift between pairs of fluorescent tubes to overcome the stroboscopic effect which tends to impair utility of fluorescent lighting may also be provided in the present invention.

The unit of the present invention may be made as a single element providing both the desired inductance and capacitance for operating the fluorescent light.

The present invention will be more clearly understood from the description and specification below when taken in connection with the drawings, in which—

Figure 1 shows the electrical circuit for a fluorescent ballast unit in accordance with the present invention.

Figure 2 shows a combination of two such units in which one is given a leading phase and the other a lagging phase.

Figure 3 shows partly diagrammatically the electrical circuit for the fluorescent ballast employing a single ballast.

Figure 3a shows the electrical circuit of Figure 3.

Figure 4 shows partly diagrammatically a modification of the arrangement of Figure 3.

Figure 4a shows the electrical circuit diagrammatically of the device shown in Figure 4.

Figure 5 shows a plan view of the ballast unit according to the present invention corresponding to the forms of Figure 3 or Figure 4, and,

2

Figure 6 shows a sectional view taken on the line 6—6 of Figure 5.

In the arrangement of Figure 1 the ballast unit comprises an inductance 1 and a capacity 2, inductance being connected in the line and the capacity being connected across the line between the lamp 3 and the adjacent inductance terminal. When the lamp is not running, its resistance is practically infinite so that under these conditions the existing circuit comprises the inductance 1 and the capacity 2 connected across the line. This latter circuit is tuned for the operating frequency as, for instance, 60 cycles, in which case the condition is fulfilled that

$$15 \quad LW = \frac{1}{CW}$$

which is a resonant condition for the circuit. Other starting conditions are as follows:

$$20 \quad Z_{in} = \frac{LW}{Q} \text{ where } Q = \frac{X_c}{R_1} X_c = \frac{1}{CW} = WL \text{ and } V_c = VQ$$

25 V_c is the voltage across the condenser. V is the voltage across the line. L is the inductance of 1. C is the capacity of 2. R_1 is the resistance in the inductance. Z is in the input impedance. $W = 2\pi$ times the frequency.

30 If in the above arrangement, R_1 is small compared to the inductive or capacitance reactance, X_1 or X_c respectively, then the voltage developed across the capacity which is the same as the voltage across the lamp may be extremely high since this voltage is equal to the line voltage times

$$35 \quad \frac{LW}{R_1}$$

It will be evident therefore, that starting of the lamp will be readily accomplished.

Under running conditions, since the inductive reactance and the capacitance reactance are equal and opposite they will cancel themselves out, one providing a leading phase and the other providing a lagging phase. The only additional consumption of power beside that used in the lamp will be that of the loss in the inductance, namely, the loss due to the quantity R_1 . The phase shift between the input voltage and the voltage across the lamp due to the inductance in the line will be somewhat less than 90° lagging.

40 45 50 In the arrangement of Figure 1, the usual fluorescent lamp arrangement is shown consisting of the two heaters 4 and 5, a heater switch 6 which opens after a short time interval and the capacitor 7 across the switch element 6.

55 If it is desired to use a circuit of two lamps, one

circuit may be provided with a phase lag of somewhat less than 90° , and the other circuit with a phase lead of somewhat less than 90° . This is illustrated in Figure 2 where the lamp 8 is arranged in the same way as the circuit of Figure 1 with a series inductance 9 and a capacity shunt 10 while the lamp 11 is provided with a series capacity 12 and an inductive shunt 13. The lamp 8 lags the line voltage in operation because of the inductance 9 while the lamp 11 leads the line voltage because of the capacity 12. The two lamps, because of their characteristics, will, therefore, have a phase difference of approximately 90° , while the circuits will have a phase difference of somewhat less than 180° , which means that each will light alternately twice in a complete cycle. The resistive reactance of the lamps when lighting will pull the phase together to approximately 90° . At 60 cycles, therefore, the occurrence of the discharge will be at the rate of 240 times per second, which by proper design can be spaced substantially uniformly from each other. As a result of this, the stroboscopic effect will be substantially eliminated.

The unit providing the capacity and inductance is illustrated somewhat diagrammatically in Figures 3 and 3a. In these figures two conductive foils or sheets 14 and 15 are wound about a central core 16 permeable to magnetic flux. The conductive foils 14 and 15 are separated by suitable insulating sheets 17. The sheets 14 and 15 provide a capacity between one another while the windings themselves provide the inductance. The circuit may be traced as follows: Commencing from one supply line 18, current will pass through the winding 14 in a clock-wise direction from the initial terminal *a* to the end terminal *c*. Current will then flow through the lead 19 to the lamp 20, out of the lamp 20 from the lead 21 to the terminal point *d* which is the beginning of the second winding 15, through the second winding 15 to the terminal *b* and out through the terminal along the supply line 22.

The equivalent circuit is set up in Figure 3a where the terminal points *a*, *b*, *c* and *d* designate the same terminals as in Figure 3 and the lamp the same lamp as in Figure 3. The inductance 23 corresponds to the winding 14 while the inductance 24 corresponds to the winding 15. Winding 23 and 24 link the same flux and have very close coupling between them.

In the arrangement of Figures 3 and 3a, it will be seen that current flows through both windings 14 and 15 in the same direction. The effective capacity between the windings 14 and 15 is, of course distributed all the way between both windings. It will be noted however, that these distributed capacities run criss-cross from the beginning of one inductance to the end of the other inductance, looking into the unit from the line side. These distributed capacities are represented by lumped capacity units in the elements 25 and 26. For resonant conditions the voltage on starting across the tube 20 will be equal to $Q \times$ the line voltage, as in the equations given above. This is of course, for resonance in the circuits providing the inductance and capacitance.

In the arrangement indicated in Figures 4 and 4a, two spirally wound foils 30 and 31 are employed as in the arrangement in Figure 3. In the arrangement of Figure 4 however, the turns of one winding, as for instance, the winding 31, are all connected together at one end of the winding roll as indicated diagrammatically in Figure 4a, where the turns of the windings 31

are all tied together. A single capacitance is, therefore, set up distributing from the windings 30 to what may be considered a single element 31 connected to the opposite side of the line, as for instance, the line 32. In Figure 4, therefore, the input side is represented by the two lines 32 and 33 while the output to the lamp is represented by the lines 32 and 34. Between the line 33 and 34 is the inductance winding 30 and across the line is the distributed capacity between the winding 30 and the shorted winding 31. The circuit of Figure 4, it will be seen, is therefore substantially the equivalent of the circuit of Figure 1 with the exception that the capacity in Figure 4a is distributed over the whole winding. The same equations apply to Figure 4a as set forth in Figure 1.

In Figures 5 and 6 there is shown an element for providing the inductance and capacitances necessary for operation of the fluorescent lamps as diagrammatically represented in the other figures. Here the roll 40 may be formed of windings of pairs of conductive foils 41 and 42 separated by insulating and dielectric elements 43. These windings may be made on a core 44 with an air gap 44' to increase the magnetic reluctance and provide partial saturation to limit open load current. Under these conditions the inductance is decreased with respect to a tuned condition or in effect the circuit is somewhat detuned. The core 44 is of material permeable to magnetic flux. If desired an open core might be used. However Figure 5 shows a closed core, the path being closed by the outside element 45. The conductive foil may be of any suitable metallic foil, as for instance, aluminum, copper or some alloy. The electrical circuit may be connected either according to the means set forth in Figures 3, 3a or 4. The distributed capacity may be tuned with inductance to resonance for the figuring of the supply source. Only one element therefore is needed, the power factor at the line will be zero and loss and heating will be kept to a minimum.

Having now described my invention, I claim:

1. A lighting circuit including a supply line, a fluorescent lamp and a fluorescent ballast unit comprising two windings of conductive foil elements having separator sheets formed as a dielectric insulator, one winding having turns connected together at one end of the winding roll and connected to one side of the supply line, the other winding being connected in series with the line, said fluorescent lamp being connected across the line after the series and shunt ballast connections.

2. A lighting circuit including a supply line and a fluorescent ballast unit comprising two windings of conductive foil elements having separator sheets formed as a dielectric insulator, one winding having turns connected together at one end of the winding roll and connected to one side of the supply line, the other winding being connected in series with the line, a fluorescent lamp being connected across the line after the series and shunt ballast connections, and a core permeable to magnetic flux around which the windings are placed.

3. A lighting circuit including a supply line and a fluorescent ballast unit comprising two windings of conductive foil elements having separator sheets formed as a dielectric insulator, one winding having turns connected together at one end of the winding roll and connected to one side of the supply line, the other winding being con-

nected in series with the line, a fluorescent lamp being connected across the line after the series and shunt ballast connections, said unit being tuned to resonance at the frequency of the supply current.
